UNITED STATES PATENT OFFICE.

CLARK H. DOWNEY, OF WEST POINT, GEORGIA.

DOLL.

1,221,157.

Specification of Letters Patent. Patented Apr. 3, 1917.

Application filed December 23, 1914. Serial No. 878,754.

To all whom it may concern:

Be it known that I, CLARK H. DOWNEY, a citizen of the United States, residing at West Point, in the county of Troup and State of Georgia, have invented certain new and useful Improvements in Dolls; and I do hereby declare the following to be a full, clear, and exact description of the invention, such as will enable others skilled in the art to which it appertains to make and use the same.

This invention has for its primary object the production of a substantially non-breakable doll in a simple, cheap, and efficient manner.

A further object is the adaptation of the features-retaining parts for rendering the structure substantially non-breakable while avoiding unwieldy weight or lack of flexibility.

With these and further objects in view, the invention comprises certain novel constructions, combinations, and arrangements of parts as will hereinafter be specified and claimed.

In the accompanying drawing:

Figure 1 is a perspective view of a fragment of a doll body and head structure with the face portion removed.

Fig. 2 is a longitudinal, vertical central section therethrough, the body portion being broken away.

Fig. 3 is a horizontal, transverse section taken on the plane indicated by line 3—3 of Fig. 2 and looking upward.

Referring to the drawing by numerals, 1 indicates a body consisting of a casing filled with cotton or like flexible fibrous material, the head portion 2 having a section at its front left flat as indicated at 3. Applied to the flat surface 3 of the head portion 2 is the face portion which consists of an artificial stone foundation 4 formed preferably of plaster of Paris and hydraulic cement, and shaped to conform to the contour of the human face or that of any other animal, according to the nature of the doll. The rear or inner surface of the foundation 4 is formed substantially flat or straight across so as to conform to the flat portion 3 when applied thereto, the edge contour of the foundation 4 conforming substantially to the curved line of the edge of the flat portion 3. Thus, the foundation 4 consists of a block of stony matter of a thickness sufficiently great to substantially insure against breakage under all ordinary conditions of usage, and yet the

block is sufficiently thin not to produce a heavy, non-flexible and unwieldy structure or to in any way interfere with the flexibility of neck 7. Fitting the exposed contour of block or foundation 4 is a chamois skin sheet 5, which covers the face portion and extends rearward about the head portion 2 in the rear of the face a sufficient distance for having the edge of the sheet of chamois skin concealed when the doll is completed either by a head covering or by a wig. Ears 5' of chamois skin are secured to sheet 5 preferably by concealed stitching but may be secured by adhesive. The stitching is indicated at 5''. The part of sheet 5 which terminates about the neck may be concealed in any appropriate manner, as by a ribbon or other decorating element connected to the head covering or applied to the neck. The edge of the sheet 5 is connected to the head portion 2 and neck portion 7 by stitching indicated at 6, and in addition thereto may, if preferred, be glued or otherwise caused to adhere to the head portion. The front portion of the sheet of chamois skin 5 is caused to conform closely to the exposed contour of the block or foundation 4 and to remain rigid therewith by being caused to adhere thereto preferably by the manner of constructing the face portion which consists in placing a sheet of chamois skin into a face matrix, the exposed or inner surface of the sheet being covered with shellac or other appropriate adhesive or cement, and then the mold or matrix is filled with the artificial stone producing material, which material is packed down with sufficient force to cause the leather and the stone to assume the contour of the matrix. The outer surface of the filling is smoothed off substantially flat and straight across, and, when the structure is completed, such outer flat surface forms the rear surface of block 4, which rests against the flat surface 3. After the mold or matrix has been filled, the parts are allowed to remain until the artificial stone has set and the adhesive at the same time impregnates the pores of the chamois skin 5 and the artificial stone, and the skin and stone are then removed and the outer surface of the chamois skin sheet is given a coating of pigment, preferably of flesh color. As soon as this has dried, the face portion is ready to be applied to the flexible head portion by having the portions of the chamois skin which extend beyond the block

4 stitched, as at 6, to the part 2. The eyes, brows, and lips may then be retouched, if desired, for giving them the required appearance. I find that in the use of chamois skin, I am able to secure the requisite porosity for insuring permanent adhesion of the leather surface to the stone base or block and at the same time, the porous nature of the chamois skin enables the application of the flesh color pigment to the outer surface in a manner causing the finished face to have the exact appearance of an ordinary bisque doll. Another mode of construction sometimes employed by me is to first cast the block 4, and then apply the skin 5, but this is not preferred.

It is, of course, apparent that in constructing the face portion, when the chamois skin is applied in the matrix, the sheet of chamois skin is sufficiently larger than the matrix to leave an edge flap entirely about the finished block 4 of a size adapting the edge flap to inclose parts of the head portion 2 for receiving the stitching 6.

25 I am aware that it has been proposed to utilize a sheet of leather, not chamois, for increasing the wearing capacity of a face of a doll and to support the leather by a thin shell of artificial stone or like substance, 30 conforming in shape to the shape of the face, but this proposed arrangement does not prevent breaking of the doll since the shell is designed merely to hold the leather or face fabric in shape, and is not adapted to withstand 35 the impact of a fall, and when broken leaves fissures which, leaving the leather without support, permits the leather to wrinkle and become distorted, and even wear loose and fall away from the face, losing its

shape and destroying the beauty and symmetry of the features of the doll. Other attempts have been made to avoid breakage by constructing the head substantially entirely of artificial stone covered by a sheet of fabric and having a small pad at the rear, 45 but this arrangement produces rigidity of the parts as well as involves excessive weight, the very presence of which tends to cause breakage when the doll is accidentally dropped. The present structure involves a 50 face portion which is neither a shell nor an approximate head but is merely a block of a thickness which will substantially prevent breakage, and yet which will not interfere with flexibility or materially add weight, 55 one of the desirable features of the block residing in the fact that it is only of the thickness incident to the filling of a face matrix so that the face block is easily constructed and is, at the same time, especially efficient 60 in use.

What I claim is:

In the art of constructing a doll, disposing in a matrix, a chamois skin covering for the face portion, an adhesive, and an artificial 65 stone portion, placing stone forming plastic material with the adhesive positioned between the materials while the adhesive and stone forming material are plastic, and forcing the materials against the skin sufficiently 70 for causing the skin to conform to the matrix.

In testimony whereof I affix my signature in presence of two witnesses.

CLARK H. DOWNEY.
